SUPPORT MEANS FOR IDLER ROLLERS

Filed Dec. 7, 1945

UNITED STATES PATENT OFFICE

2,455,100

SUPPORT MEANS FOR IDLER ROLLERS

Franklin N. Smith, Cedar Rapids, Iowa

Application December 7, 1945, Serial No. 633,318

7 Claims. (Cl. 198—192)

1

My invention relates to improvements in support means for idler rollers, and more particularly to novel means for clamping troughing roller fixtures to their supports, the primary object of the invention being to provide means of this character which enable more efficiently, quickly, and securely clamping such fixtures on their supports and removing the same therefrom.

Another important object of the invention is to provide clamping means of the character indicated which act laterally upon the supports, whether of channel or of angle iron or other type, in either outward or inward directions, and at the same time substantially eliminate overstressing or distorting the supports.

Other important objects and advantages of my invention will appear in the following description and appended drawing, wherein illustrative embodiments of the invention are set forth only as examples.

In the drawing:

Figure 1 is a fragmentary side elevation of an arrangement according to the invention utilizing a channel type support frame with an angulated troughing roller, with the clamps acting laterally outwardly.

Figure 2 is a fragmentary left-hand end elevation of Figure 1.

Figure 3 is an enlarged vertical transverse section taken on the line 3—3 of Figure 1.

Figure 4 is a fragmentary side elevation of another arrangement according to the invention, with the clamps acting laterally inwardly.

Referring in detail to the drawing, the numeral 5 generally designates a type of conveyor belt troughing roller such as disclosed in my co-pending application, filed December 7, 1945, Ser. No. 633,317, (Patent No. 2,446,616), for "Bearing structure for conveyor rollers and the like," involving a hexagonal nut 6 which is removably inserted in a conformingly shaped slot 7 in the upper end of the angulated portion 8 of the T-section stand 9 for quick removal and installation. The flat base 10 of the stand 9 is designed to rest upon the horizontal support member 11, with bolts 12 traversing the base 10 and the web or flange 13 of the support member at opposite sides of the stand 9. The opposite end of the roller 5 may have any suitable means of removable support (not shown) capable of taking the thrust of the angulated roller.

In the embodiment shown in Figures 1 and 2 of the drawings, the horizontal support member 11 is an inverted channel which rests at its ends upon the laterally inturned flanges 14 and 15, respec-

2

tively, of the corresponding upright 16 and 17, the said flanges having slanting lower surfaces, to cooperate with the related clamps 18 and 19, respectively.

The stationary hook-shaped clamp 19 has its shank 20 welded or otherwise suitably secured to a spacer 21 secured to and between the sides of the channel support 11 near its lower edges, as indicated in the right hand portion of Figure 1 of the drawings, the crook 22 of the clamp reaching downwardly below the channel and around the flange 15.

At the left hand end of the channel 11, the spread L-shaped clamp 18 has a vertically arranged shank 23 terminating in the angulated foot 24 which extends below the channel and engages under the slanting surface of the flange 14 of the upright 16. The shank 23 is traversed by a bolt 25 whose head abuts the inner side of the shank and whose body rests upon a spacer 26 secured to and between the sides of the channel 11 near their lower edges. The bolt 25 traverses also a plate 27 abutting the end of the channel and against which the nut 28 is turned in tightening the bolt. When the nut 28 is tightened the channel 11 is forced in a right hand direction so that the right hand clamp 19 wedges on the flange 15, while at the same time the left hand clamp 18 wedges on the flange 14, thereby rigidly securing the channel 11 to the conveyor frame uprights 16 and 17. It is obvious that simply loosening the nut 28 permits easy and quick removal of the channel 11 from these uprights. As indicated in Figure 1 of the drawing the upright 16 may have another laterally inwardly directed slant face flange 29 on which may be mounted by means of the bolt 30, the upper and lower elements 31 and 32 of a bracket 33, whose vertical part 34 may be slotted at 35 to removably accommodate the hexagonal nut 6—a of a horizontal roller 5—a, having suitable support means (not shown) for its opposite end.

Referring now to the embodiment of my invention shown in Figure 4 of the drawings, the frame uprights 16—a and 17—a having laterally outward flanges 14—a and 15—a, respectively, instead of the inturned flanges of the above described embodiment, and the under surfaces of these flanges are not angulated, but the outer edges of the flanges are slotted with angulated edges to cooperate with the clamps, as indicated at 36 and 37, respectively.

The stationary clamp 19—a is hook-shaped with its shank 20—a horizontal and secured upon the spacer 21—a secured to the sides of the channel, the spacer having on its inward end a de-

pending extension 40 in the form of a brace, to engage and support the inner side of the upright 16—a to prevent distortion when the clamping pressure is exerted.

The adjustable clamp 18—a at the left hand end of the channel 11—a has its vertical shank 23—a on the bolt 25—a between the nut 28—a and the end of the channel from which it is outwardly spaced. The body of the bolt traverses a block 28 fixed in the channel, with the head of the bolt engaging the inner side of said block. An angle brace 39 in support relation to the channel 11—a and the inner side of the upright 16—a is provided to prevent distortion thereof when the clamping pressure is applied. It is obvious that tightening the nut 28—a will force the channel 11—a in a left hand direction, thereby forcibly engaging the right hand clamp 19—a with the flange 15—a, while at the same time the clamp 18—a forcibly engages the related flange 14—a, thereby securely clamping the horizontal channel 11—a on the uprights. As in the case of the first described embodiment, the stands for the rollers are to be bolted to the channel 11—a; and the channel may be quickly removed from the uprights by loosening the nut 28—a sufficiently to permit disengagement of the clamps from the flanges of the uprights with which they are engaged.

I claim:

1. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said clamping means comprising a stationary clamp fixed at one end of said horizontal member, a laterally adjustable clamp mounted at the opposite end of said horizontal member, and operating means for said adjustable clamp for moving said adjustable clamp in a direction to forcibly engage the clamps with the corresponding flanges.

2. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said flanges being laterally inturned toward each other, and said transversely acting means comprising clamps for engaging the inner edges of the said flanges, and operating means for moving at least one of the clamps in a laterally outward direction so as to forcibly engage the clamps with the said flanges.

3. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said flanges being laterally outwardly directed away from each other, and said transversely acting means comprising clamps for engaging the outer edges of the

said flanges, and operating means for moving at least one of the clamps in a laterally inward direction so as to forcibly engage the clamps with the flanges.

5. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said clamping means comprising a stationary clamp fixed at one end of said horizontal member, a laterally adjustable clamp mounted at the opposite end of said horizontal member, and operating means for said adjustable clamp for moving said adjustable clamp in a direction to forcibly engage the clamps with the corresponding flanges, said operating means comprising a bolt operatively connecting a portion on said horizontal member and said adjustable clamp and a nut on the bolt threadable in opposite directions to tighten and loosen the clamps on the flanges of the uprights.

6. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said clamping means comprising a stationary clamp fixed at one end of said horizontal member, a laterally adjustable clamp mounted at the opposite end of said horizontal member, and operating means for said adjustable clamp for moving said adjustable clamp in a direction to forcibly engage the clamps with the corresponding flanges, said operating means comprising a bolt operatively connecting a portion on said horizontal member and said adjustable clamp and a nut on the bolt threadable in opposite directions to tighten and loosen the clamps on the flanges of the uprights, said nut being threadable in the loosening direction sufficiently to permit complete disengagement of the clamps from the flanges to permit free removal of said horizontal member from said upright.

7. In combination, a belt conveyor frame including a pair of uprights having lateral flanges at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said flanges being laterally inturned toward each other, and said transversely acting means comprising clamps for engaging the inner edges of the said flanges, and operating means for moving at least one of the clamps in a laterally outward direction so as to forcibly engage the clamps with the said flanges, said operating means comprising a bolt traversing said one clamp with the head of the bolt abutting the inward side of the clamp, an end portion on said horizontal member also traversed by said bolt, and a nut threaded on the bolt to engage the laterally outward side of said portion on the horizontal member.

8. In combination, a belt conveyor frame including a pair of uprights having lateral flanges

at their upper ends, a horizontal member extending between said uprights and resting upon said flanges, said horizontal member being arranged for the support of a troughing roller or the like mounted thereon, transversely acting means engageable with said flanges for clamping said horizontal member on said uprights, said flanges being laterally outwardly directed away from each other, and said transversely acting means comprising clamps for engaging the outer edges of the said flanges, and operating means for moving at least one of the clamps in a laterally inward direction so as to forcibly engage the clamps with the flanges, said operating means comprising a bolt traversing said one clamp, a portion on the horizontal member also traversed by said bolt

with the head of the bolt abutting the laterally inward side of said portion, said one clamp being positioned laterally outwardly from said portion, and a nut threaded on the bolt to engage the laterally outward side of said one clamp.
